AUTOGRAPHIC REGISTER

John E. Hook, 221 Lucas St., Richmond Hill,
Ontario, Canada
Filed Aug. 20, 1962, Ser. No. 217,843
12 Claims. (Cl. 282—13)

This invention pertains to improvements in autographic registers and, more particularly, to improvements in cabinet structure and mechanism of such registers.

It is conventional practice to construct autographic registers by locating a plurality of partitions in a housing that is somewhat complicated and therefore costly to produce. Carbon paper located in such autographic registers is normally difficult to replace, one sheet of carbon paper normally being replaced at a time.

It is an object of this invention to provide an autographic register providing extremely inexpensive and simple method of manufacturing, complete register consisting basically of only two parts.

It is a further object of this invention to provide an autographic register consisting basically of a housing and a single, easily removable partitioning means.

It is still a further object of this invention to provide an autographic register containing removable partitioning means that is entirely self-contained, this one partitioning means containing both used and unused forms removable from the housing in one operation.

It is another object of this invention to provide an autographic register containing a simple partitioning member, one portion of which may act as a writing table for a plurality of forms.

It is still another object of this invention to provide an autographic register containing partitioning means, folded out of one piece of material, providing compartment for unused forms and compartment for used forms, extremely simple retaining means for torn off individual sheets of used forms, being located at the entrance opening of the compartment for such used forms.

It is a further object of this invention to provide an autographic register having provision for accommodating and dispensing carbon paper in roll form.

It is still a further object of this invention to provide an autographic register permitting utilization of a simplified form of locating each individual set of forms in writing position by utilization of cross perforations on such forms.

These and other objects and features of this invention will become apparent when taken in conjunction with the accompanying drawings in which:

FIG. 1 is a perspective view of one form of autographic register utilizing the present invention.

FIG. 2 is a plan view of the autographic register shown in FIG. 1.

FIG. 3 is a longitudinal cross-section of the autographic register shown in FIG. 2, taken on the line 3—3.

FIG. 4 is an end view of the autographic register as shown in FIG. 2 taken in direction of arrow 4.

FIG. 5 is a longitudinal cross-sectional view of an alternative method of utilizing the partitioning means of the present invention, taken on the line 3—3 in FIG. 2.

FIG. 6 is a fractional, perspective view of an alternative method of tearing the forms.

Referring to FIGS. 1, 2 and 3, the example shown of an autographic register utilizing the present invention includes a cabinet 10 consisting of a top 11, downwardly depending side walls 12 and 13 from marginal side edges of top 11, downwardly depending end walls 14 and 15 from marginal end edges of top 11, end wall 15 being the rear wall, end wall 15 containing an opening 16 into an upper part of cabinet 10, opening 16 being defined by an upper edge 17 and a lower concavely curved edge 18 pro-

2

viding a portion 19 of rear wall 15 on either side of aperture 16, portion 19 being adapted to provide stop means for sheets located in upper portion of cabinet 10 thereby preventing such sheets from inadvertently falling out thereof.

5 A double folded partitioning member 20 made up of one sheet of material folded in a Z form substantially as shown, is adapted to be removably and pressurably located into cabinet 10 and maintained in cabinet 10 by 10 means of knobs 21 located internally of cabinet 10 and corresponding indentations 22 located externally of partitioning member 20.

Through folding partitioning member 20 in the manner shown, supply compartment 23 is adapted to receive a 15 pack of folded endless forms 24, each form 24 consisting of a plurality of forms as shown at 25 and 26, forms 25 and 26 being adapted to progressively proceed over hairpin bend 27 and along upper surface 28 of writing table 29 of partitioning member 20, the locating of forms 25 20 and 26 in correct writing position being accomplished by locating means such as, for instance, shown in this figure in the form of stop pin 30 adapted to locate in corresponding holes 31 in forms 25 and 26.

Carbon paper 32 may be located between forms 25 and 26 by clip means 33 retained in partitioning member 20 by a pin 34.

Alternative or supplementary stop means are shown in FIGS. 3 and 4 located in opening 16 comprising an upwardly directed resilient stop member 35 attached to 30 upper surface of dividing partition 36 of partitioning member 20, a similar resilient, downwardly depending stop member 37 being located underneath writing table 29, substantially adjacent stop member 35.

Closure portion 27a of partitioning member 20 35 may be made resilient and biased upwards towards hairpin bend 27 to provide tensioning means on forms 25 and 26 to facilitate maintaining forms 25 and 26 in a stretched out configuration on top of writing table 29.

Closure portion 27a may be made sufficiently flexible 40 to permit folding down the extreme end thereof towards base portion 36a of partitioning member 20 to facilitate insertion or removal of endless form pack 24.

Pins 30 may be made with a slightly oval-cross section, 45 having the longest axis of the oval parallel with the longitudinal direction of autographic register 10 to facilitate insertion of pins 30 into round hole 31 of forms 25 and 26.

A modified version of the present invention is shown 50 in FIG. 5 where Z-shaped partitioning member 38 has forward hair pin bend 39 of upper compartment 40 formed to a substantially sharply protruding edge 41 adapted to provide that upon endless forms 42 and 43 being pulled over edge 41 and over writing table 44 until 55 a transverse perforation on forms 42 and 43 reaches edge 41, at which time the operator will feel a slight stop in the forward motion of forms 42 and 43 due to sudden folding of forms 42 and 43 as resistance to folding of the forms at the perforation location is considerably less than such resistance at other locations on forms 42 and 43 60 whereby the operator is able to feel that the form now has been located in writing position and therefore does not pull this any further until he again requires a new form drawn out.

65 At forward end 45, bracket means may be located at each side of base portion 46 of partitioning member 38 to hold a transverse container 47 of pear shaped cross section having a transverse opening 48 at the upper end thereof situated substantially adjacent to forward hair pin bend 39 of partitioning member 38, container 47 being adapted to receive a replaceable roll of carbon paper 49 one end 50 of roll 49 progressing through opening 48 and over writing table 44 between endless

form 43 progressing from storage chamber 51 adjacently along and around hair pin bend 39 and over writing table 44 directly beneath carbon paper 50. Second endless form 42 progresses simultaneously beneath and around container 47 and over writing table 44 directly above carbon paper 50 upon an operator pulling both forms at their extreme end 52 to locate a new set of forms in place for operation.

Upwardly biased spring 53 may be located on container 47 to provide further tensioning of form 43 against partitioning member 38 in order to make more pronounced the stop action of the perforated form over edge 41.

FIG. 6 illustrates a method of facilitating tearing of the forms after filling these out, comprising a serrated tear off plate 54 hingeably located rearwardly of cabinet 10, providing resilience to the tearing operation. Hinge portion 56 of plate 54 may be formed directly in the plastic and thereby provide elastic resiliency of plate 54.

Partitioning members 20 and 38 may be made with open sides, thereby facilitating insertion or removal of form packs and used form sheets, method of operation of the automatic register being to forcibly remove partitioning member 20 or 38 from cabinet 10 by applying pressure downwards on writing table 29 or 44 while holding up cabinet 10 whereby partitioning member is forced out of the cabinet to expose open sides of partitioning member whereafter form pack and individual sheets of used forms may be slidingly removed sideways out of the partitioning member or slidingly inserted sideways into partitioning member. Carbon paper may be inserted or replaced upon removal of endless form and before insertion of new endless form into the partitioning member, the same applying to replaceable rolls of carbon paper in FIG. 5.

Retaining means for carbon paper 50 may be provided by biasing two sides of opening 48 of container 47 towards each other thereby providing that extra pressure may be exerted upon upper form 42 through writing table opening 29a in cabinet 10 whereby pull on ends 52 of forms 42 and 43 will provide that a portion of carbon paper 50 is drawn out with forms 42 and 43 to provide new carbon paper portion upon the utilized carbon paper being worn out.

No locating pins are required in alternative method shown in FIG. 5 for location of paper forms in writing position, this being accomplished solely through feeling the difference in pull upon transverse perforation reaching edge 41.

Referring to FIG. 5, outwardly extending tab means 57 is attached to spring 53, tab means 57 extending through slot 58 in side of cabinet to provide manual release means for spring pressure applied by spring 53 on form 43 during insertion and removal of form packs from partitioning member 38, or to ease tension on form 43 upon this being required.

The general design of the individual parts of the invention as explained above may be varied according to requirements in regards to manufacture and production thereof, while still remaining within the spirit and principle of the invention, without prejudicing the novelty thereof.

The embodiments of this invention in which an exclusive property or privilege is claimed are defined as follows:

1. An autographic register, including a cabinet having a top and downwardly depending side walls and end walls, a writing opening in said top, said cabinet having an open base, a Z-shaped partitioning member adapted to be pressurably and removably received into said open base of said cabinet, said partitioning member being adapted to be contained substantially entirely within said cabinet, said partitioning member being formed out of one longitudinal sheet of material formed in a double hair pin bend, upper portion of said partitioning member being substantially horizontal and located directly

adjacent and beneath said writing opening, said partitioning member having a central horizontal partition joined to said writing table by a first hair pin bend, said partitioning member having a base portion joined to said central portion by a second hair pin bend located at opposite end of said partitioning member in regard to said first hair pin bend, retaining means inside said cabinet adapted to cooperate with retaining means on said partitioning member to pressurably and removably retain said partitioning member in said cabinet, carbon paper retaining means located in said partitioning member, a chamber formed between said base portion and said central portion adapted to receive a pack of sets of endless forms, and stop means located on said partitioning member adapted to locate individual sets of said endless forms in writing position, said writing plate and said central portion forming a storage chamber for used forms, and stop means adapted to permit insertion of forms through open end of said storage chamber for used forms yet prevent said used forms from inadvertently being discharged through said open end.

2. An autographic register as claimed in claim 1 in which said stop means for said used forms comprises a resilient upwardly depending tab located in said open end of said storage chamber, in cooperation with a downwardly depending resilient tab located adjacently said upwardly depending tab.

3. An autographic register as claimed in claim 1 in which said stop means for said used forms comprises an opening cut out of one end of said cabinet directly adjacent said opening of said storage chamber for said used forms, said opening in said cabinet having an upper edge parallel with said writing table portion, a concave curve extending from one end of said horizontal edge to the other end of said horizontal edge thereby to provide that a portion of said rear wall of said cabinet obstruct a portion at each side of said storage chamber for said used forms.

4. An autographic register as claimed in claim 1 in which the extreme end of said base portion of said partitioning member is folded upwards towards said first hair pin bend, said upwardly folded portion being resiliently biased upwards towards said first hair pin bend to exert friction force on said form progressing past said first hair pin bend.

5. An autographic register as claimed in claim 1 in which said carbon retaining means comprises a transverse clamp having carbon paper clamped therein, said transverse clamp having peg means adapted to removably attach and hold said clamp means on said writing table portion.

6. An autographic register as claimed in claim 1 in which said stop means for location of said form in said writing position consists of a plurality of upwardly depending pins located at extreme end of said writing table portion, said locating pins having an oval cross-section.

7. An autographic register as claimed in claim 1 in which said first hair pin bend provides a substantially sharp horizontal edge parallel with the forward edge of said first hair pin bend, said stop means for location of said forms in said writing position being provided by cooperation of said sharp edge with transverse perforation in said forms.

8. An autographic register, including a cabinet having a top and downwardly depending side walls and end walls, a writing opening in said top, said cabinet having an open base, a Z-shaped partitioning member adapted to be pressurably and removably received into said open base of said cabinet, said partitioning member being adapted to be contained substantially entirely within said cabinet, said partitioning member being formed out of one longitudinal sheet of material formed in a double hair pin bend, upper portion of said partitioning member being substantially horizontal and located directly adjacent and beneath said writing opening, said partitioning member

having a central horizontal partition joined to said writing table by a first hair pin bend, said partitioning member having a base portion joined to said central portion by a second hair pin bend located at opposite end of said partitioning member in regard to said first hair pin bend, retaining means inside said cabinet adapted to cooperate with retaining means on said partitioning member to pressurably and removably retain said partitioning member in said cabinet, carbon paper retaining means located in said partitioning member, a chamber formed between said base portion and said central portion adapted to receive a pack of sets of endless forms, and stop means located on said partitioning member adapted to locate individual sets of said endless forms in writing position, said writing plate and said central portion forming a storage chamber for used forms, and stop means adapted to permit insertion of forms through open end of said storage chamber for used forms yet prevent said used forms from inadvertently being discharged through said open end, said carbon paper means comprising container means attached to extreme end of said base plates of said partitioning member, said container means being located parallel with one end of said partitioning member containing said first hair pin bend, a transverse opening located at an upper end of said container, said opening being parallel with and directly adjacent to said first hair pin bend, replaceable carbon paper roll means located in said container, one end of said carbon paper being adapted to extend through said opening onto said writing table.

9. An autographic register as claimed in claim 8 in which said opening of said container has two sides of said opening pressurably biased towards each other.

5 10. An autographic register as claimed in claim 8 in which spring means are attached to said container, said spring means being biased towards at least one of said forms passing between said spring means and said central portion of said partitioning means.

10 15 11. An autographic register as claimed in claim 1 in which serrated tear off means are located at extreme end of said writing plate, said serrated tear off means being resiliently attached to said writing table.

15 20 12. An autographic register as claimed in claim 8 in which spring means are attached to said container, said spring means being biased towards at least one of said forms passing between said spring means and said central portion of said partitioning means, manual release handle means attached to said spring means, slot means located in said cabinet, said slot means permitting said release handle means to protrude therethrough for manual operation of said lever means.
